MECHANICAL TOY

Harry J. Criner, Davenport, Iowa, assignor of one-half to A. G. Bush, Davenport, Iowa

Application January 24, 1944, Serial No. 519,549

2 Claims. (Cl. 46—132)

My invention relates to improvements in mechanical toys and the objects of my invention are to provide a toy comprising a rotatable body, preferably circular, mounted upon a string or pair of strings, with differential winding drums for the strings so arranged that pulling upon the outer ends of the strings in opposite directions will cause the body to rotate and simultaneously travel longitudinally of the strings, and relaxing the strings, when held in the vertical position, will allow the body to descend from the upper end of the string to the lower end thereof. Other objects will appear from the description.

I attain these objects by the means illustrated in the accompanying drawings, in which:

Figure 1 is a vertical half section of my toy on the middle line 1—1 of Figure 2, but with the outer ends of the strings broken away;

Figure 2 is a vertical section on the line 2—2 of Figure 1;

Figure 3 is a partial sectional view of a modified form of apparatus on the line 3—3 of Figure 4;

Figure 4 is a vertical section on the line 4—4 of Figure 3;

Figure 5 is a side elevation of my toy with portions of the strings broken away;

Figure 6 is a detail sectional view of the center piece in Figure 1;

Figure 7 is a sectional view of the belt plate of the form shown in Figure 3;

Figures 8 and 9 show a modification comprising the addition of an animal or other figure pivotally mounted upon the side plates.

Similar numerals refer to similar parts throughout the several views.

The body of my toy is preferably circular and composed of two side pieces 1 and 2 rigidly mounted upon a unitary shaft 5 and spaced apart thereon.

The side pieces 1 and 2 may be composed of wood, metal or any suitable material, but I prefer to form them of solid pieces of wood or plastic.

Formed integral with the side piece 1 or rigidly united thereto, is the larger drum 3. Formed integral or united to the other side piece 2 is the smaller drum 4. These drums may vary in size and proportions, but I prefer to have the smaller drum approximately half the diameter of the larger drum. The side pieces 1 and 2 and the drums 3 and 4 are rigidly mounted upon a shaft or pin 5 which may be secured to the side pieces and drums by a press fit or may be firmly united thereto by the head 6 formed upon one end of the shaft and a nut 7 threaded upon the other end of the shaft, or by any other suitable means

which will hold the two side pieces in their fixed relative position.

A spacer 8 is mounted upon the shaft 5 between the drums 3 and 4 so as to spread them apart enough to clear the center plate 9. A center plate 9 is journaled on the spacer 8 which rotates freely therein. The plate 9 is preferably formed with peripheral flanges 10 and 11 extending laterally therefrom and is arranged to permit free revolution of the side members 1 and 2.

Upon the larger drum 3 a strong flexible string or cord 14 is wound having one end attached to the drum 3 and with its opposite end extending outwardly through an opening 12 formed in the lower portion of the flange or periphery 11 of the center plate.

To the smaller drum 4 a similar, although shorter, string or cord 15 is attached in a position to be wound thereon as the drum is revolved and with its outer end projecting outwardly through the opening 13 in the flange 10 and opposite the opening 12.

The openings 12 and 13 may be arranged directly opposite each other as shown in Figures 2 and 4 in order to give a certain symmetry to the apparatus and when so arranged, the openings should be provided with rounded edges to cut down friction with the cord, but it is obvious that the openings may be somewhat extended along the circumference of the band 21 and that friction may be further reduced by locating the openings on lines tangential to the drums respectively and parallel to the vertical axis of the apparatus.

To the outer ends of the strings, I attach rings 16 and 17, or other suitable means by which they may be easily held and operated manually.

In order to increase the attractiveness of the toy, the sides may be painted or decorated with any desired form of ornamentation.

As an additional matter of interest, small figures 19 of plastic or cardboard or other suitable material, may be pivotally mounted on suitable pivot pins 20 driven into or secured in the outer surfaces of one or both of the side plates.

In the alternate form shown in Figures 3 and 4, the center plate 9 is omitted and the belt plate or band 21 is mounted in annular grooves 22 formed in the inner faces of the side pieces, with sufficient play to permit the side pieces to revolve freely thereon while the band is held against rotation.

When so arranged, openings 23 and 24 will be formed on the opposite sides of the band for the strings to pass through and the spacer 8 will

be omitted, but its place may be taken by a circular plate 25 which will act to keep the strings from being displaced laterally from their respective drums.

My toy is preferably operated with the strings held in vertical position.

The string 14 from the larger drum, passes out through the lower opening 12. The string 14 should be wound upon the drum 3 before the side pieces are secured together by the shaft 5 and the outer ends of the strings passed out through their respective openings.

When the string is then held in vertical position and traction applied to pull the rings 16 and 17 in opposite directions, the string 14 will unwind from the drum 3 and cause the drum 3 to revolve, carrying with it the shaft 5 and the side members 1 and 2, as well as the smaller drum 4. At the same time the string 15 will be wound upon the smaller drum 4 and the body of the toy will move upwardly a distance approximately equal to the length of the string wound on the smaller drum.

At any point in its travel, the upward movement of the body may be stopped by releasing the tension upon the string on the larger drum and if desired, the strings may be held loosely enough to permit the force of gravity to cause the body to descend. As it descends it of course will continue to rotate and the string 15 will be unwound from the drum 4 and the string 14 rewound upon the drum 3. The form of toy shown in Figures 3 and 4 can be operated in the same way.

As the drums and side pieces revolve, centrifugal force will cause the figures 19 to fly outwardly upon their pivots 20, depending to some extent upon the speed with which the body is revolving.

In Figure 8 I have shown the outer portions of the string in horizontal position above a base or table 33 upon which the body may roll, with a figure 31 pivotally mounted upon the pivot pins 32 secured in the side plates 1 and 2.

In the drawings I have shown this figure in the form of a horse. The front feet of the horse may be pivoted to the outer ends of the shaft 5 extended, or may be pivoted upon pivot pins 32 secured to one side of the center shaft, and when so secured the front end of the horse will move up and down as the body revolves or rolls along upon the table 33. The figure is preferably made of very light Celluloid or other plastic so as not to interfere with the revolution of the side members. When traction is exerted in opposite directions upon the rings 16 and 17, the figure will

advance with the body rolling along in the direction of the arrows, unwinding the string 14 from the larger drum and rewinding the string 15 upon the smaller drum. When desired to move the figure in the opposite direction, the ring 16 is held in fixed position and the ring 17 released. The body can then be manually pulled or rolled by hand in the opposite direction and the string 15 will unwind from the smaller drum and the string 14 will rewind upon the larger drum or the string can be shifted to a vertical position with the ring 16 uppermost so that the force of gravity can cause the body to descend to the ring 17 after which the operation can be repeated.

Various modifications may be made in the shape, proportions and arrangement of the members without departing from the spirit of my invention and I do not limit my claims to the precise forms shown.

I claim:

1. A mechanical toy comprising a central shaft, a pair of solid circular side members rigidly united to the shaft and having parallel plane inner faces spaced apart, differential winding drums co-axially united to the side members respectively on their inner faces, annular grooves formed at the outer edges of the inner faces of the side members, an annular band interposed between the side members with its edges fitting loosely in said annular grooves, cords or strings having their inner ends united respectively to said winding drums and windable thereon in opposite directions, string guide openings formed in approximately opposite sides of the annular band and through which the outer ends of said strings pass respectively.

2. A mechanical toy comprising a central shaft, a pair of solid circular side members rigidly united to the shaft and having parallel plane inner faces spaced apart, differential winding drums co-axially united to the side members respectively on their inner faces, an annular band interposed between the side members at or near the outer edges thereof, and means formed upon the inner faces of the side members at or near the outer edges thereof to form a loosely fitting seat for said annular band in which the annular band may be held stationary while the side members revolve, cords or strings having their inner ends united respectively to said winding drums and windable thereon in opposite directions, string guide openings formed in approximately opposite sides of the annular band and through which the outer ends of said strings pass respectively and are freely movable.

HARRY J. CRINER.
